CLAIM

We claim the ornamental design for a data capture device, as shown and described.

DESCRIPTION

FIG. 1 is a front perspective view of a data capture device;
FIG. 2 is a rear perspective view thereof;
FIG. 3 is a front plan view thereof;
FIG. 4 is a rear plan view thereof;
FIG. 5 is bottom view thereof;
FIG. 6 is a top view thereof;
FIG. 7 is a first side view thereof; and
FIG. 8 is a second side view thereof.
FIG. 9 is a front perspective view of the data capture device
according to a second embodiment;
FIG. 10 is a rear perspective view thereof;
FIG. 11 is a front plan view thereof;
FIG. 12 is a rear plan view thereof;
FIG. 13 is a bottom view thereof;
FIG. 14 is a top view thereof;
FIG. 15 is a first side view thereof; and,
FIG. 16 is a second side view thereof.

Broken lines and unshaded portions contained within broken
lines depict portions of the data capture device that form no
part of the claimed design but are shown for illustrative
purposes.
